UNITED STATES PATENT OFFICE

97,415

DESIGN FOR A TEXTILE FABRIC

Samuel Sheindelman, Lawrence, N. Y.

Application July 29, 1935, Serial No. 57,858

Term of patent 3½ years

To all whom it may concern:

Be it known that I, Samuel Sheindelman, a citizen of the United States, residing in Lawrence, Nassau County, New York, have invented a new, original, and ornamental Design for Textile Fabrics, of which the following is a specification, reference being had to the accompanying drawing, forming part thereof.

The figure in the drawing is a plan view of a piece of the textile fabric constituting the design.

The design includes a plurality of spaced-apart,

vertical ribs, said ribs being substantially half the width of the intermediate areas. The weave in the ribbed areas is in the nature of a water wave and extends longitudinally of the rib. The weave in the intermediate areas is an irregular waffle stitch and extends generally transversely of the areas. The waffle stitch is of a much looser character than the weave in the ribbed areas.

I claim:

The ornamental design for a textile fabric as shown and described.

SAM'L SHEINDELMAN.
